UNITED STATES PATENT OFFICE

HENRY J. GILBERT, OF SAGINAW, MICHIGAN, ASSIGNOR TO SAGINAW MANUFACTURING CO., OF SAGINAW, MICHIGAN, A CORPORATION OF MICHIGAN

FOLDING IRONING TABLE

Application filed September 8, 1928. Serial No. 304,769.

My invention relates to folding tables and is more particularly adapted to collapsible ironing boards of the type in which the board is provided with legs which fold against it, 5 so the device occupies little space when folded.

An object of my invention is to provide a board of such character in which the legs are braced to combine unusual rigidity with simplicity and compactness and ease and convenience of manipulation.

These advantages are attained by a novel arrangement of the legs with certain connecting braces and strut members arranged to operate telescopically when the table is collapsed or extended, and to present a neat and pleasing appearance.

The essential elements of my improvement will be more particularly pointed out in the appended claims wherein the invention is defined.

With the foregoing and certain other objects in view, which will appear later in the specification, my invention comprises the devices described and claimed and the equivalents thereof.

In the drawings Fig. 1 is a plan view of the under side of the table, collapsed.

Fig. 2 is a side view of the table extended.

Fig. 3 is an end view of the same.

Fig. 4 is a longitudinal sectional view of a preferred form of latch.

Fig. 5 is a plan view of the same.

As is clearly shown in the drawings, the folding table consists of the board 1 and centrally arranged front leg 2 hinged to the board, preferably near an end thereof. Leg 2 is in the form of a triangular framework. It is normally inclined forwardly and downwardly when the table is extended ready for use. Near the lower free end of the front leg and pivotally connected to it is a strut member 3 whose upper end is pivoted to the board at some point 4 slightly rearward of the lower end of the strut. A pair of legs 5, 5 are hinged to the board near its rear corners in the manner shown in my Patent No. 1,627,557.

The downwardly inclined front leg 2 and the upright rear legs 5 are connected together by telescopic tie-rods 6 whose front ends 6

are close together and the rear ends 6^b are spread apart to their respective points of attachment on the rear legs of the table, thereby constituting in conjunction with the rear legs and inclined front leg a pyramidal braced structure of great rigidity.

Similarly the inclined front leg 2 and the strut 3 in conjunction with the board 1 form a pyramidal structure. The two hypothetical pyramids have the same apex, namely, the common point of attachment of the strut, tie-rods and front leg. They have a common side, defined by the plane of the front leg 2. The base of one pyramid is defined by the plane of the two back legs, the base of the other pyramid being the board.

This double pyramidal structure imparts stability in the ordinary use of the board, and the members although light combine to produce a rigid table support. The strut 3 carries the weight of the front and middle parts of the board and transmits the resultant downward thrust to the front leg at a place near its free end.

In construction the strut member 3 is telescopic, being composed of two or more sections slidably one within the other as for example an inner tube 3^a and an outer tube 4^a. These tube sections are releasably secured together by a latch, which may be of the kind shown in Figs. 4 and 5, although the construction and mode of operation of the latch may be varied to any extent desired without departing from my invention as set forth in the claims.

The form of latch shown in the drawings is a bowed spring 7 slightly stressed and inserted lengthwise into the inner tube 3^a so its middle or convex part bears against the inner wall of the tube and its ends tend to thrust outwardly against the opposite face of the cylindrical wall. One end 7^a of the spring is received in a recess formed in the tube wall and the other end of the spring is a latch that extends through a slit in the tube and projects out therefrom to present a depressible thumb piece 7^b for engagement in a slit 8 of the outer tube 4^a. Preferably two such springs and thumb pieces are employed, as shown, to pre-

vent the sections 3^a, 4^a from moving in either direction when the board is extended.

The tie-rods 6, 6 are also telescopic and are equipped with latches in the same manner as the strut member 3.

5 The manipulations for collapsing and extending the table are greatly simplified by employing the telescopic strut and tie-rods in conjunction with the hinged front and rear legs.

10 To collapse the table it is either turned upside down or stood on end. The latch 7^b in tie-rod 6 is depressed and leg 5 is swung forward, as indicated by the arrow, Fig. 2, the tie-rod 6 shortening by telescoping. Similarly the latch of strut 3 is then depressed and the front leg is folded flat against the under side of the board, the strut 3 telescoping and shortening and taking the position indicated 15 by dotted lines in Fig. 3. This telescoping action of the strut is due to the fact that its upper pivotal connection 4 to the board 1 is rearward of its lower connection, as indicated at X.

20 Having thus described my invention, what I claim and desire to secure by Letters Patent is:

1. In a folding ironing table a board, a centrally arranged front leg hinged to the board 30 near an end thereof and normally inclined forwardly and downwardly, a strut member pivotally connected to said front leg near the free end thereof and pivotally connected to the board, rear legs hinged to the board near 35 the rear corners thereof, tie-rods hinged at their ends respectively to said front leg and to said rear legs, said strut member and tie-rods each made up of sections slidably one within the other and a latch adapted to releasably secure said sections in extended position.

40 2. In a folding ironing table, a board, a centrally arranged front leg hinged to the board and normally inclined forwardly and downwardly, a strut member pivotally connected to said front leg and to the board, rear legs hinged to the board, tie-rods hinged at their ends respectively to said front leg and to said rear legs, said strut member and tie-rods each including sections slidably one relatively to the other and a latch adapted to releasably secure said sections in extended position.

45 3. In a folding ironing table a board, a centrally arranged front leg hinged to the board and normally inclined forwardly and downwardly, a strut member pivotally connecting said front leg and board, rear legs hinged to the board, tie-rods hinged at their ends respectively to said front leg at the point of pivotal connection of said strut and to said rear legs, said strut member and tie-rods each including sections slidably one relatively to the other and a latch adapted to releasably 50 secure said sections in extended position.

4. In a folding ironing table, a board, a leg hinged to the board and normally inclined forwardly and downwardly, a telescopic strut member pivotally connecting said leg and board, rear legs hinged to the board, telescopic tie rods each hinged at one end respectively to said front leg at the point of attachment of said strut member, and hinged at its other end to said upright legs, and means adapted to releasably secure said telescopic members in extended position.

70 75 In testimony whereof, I affix my signature.
HENRY J. GILBERT.
